BENDING MACHINE

Edward J. De Witt, Winnetka, Ill., assignor to
 Wallace Supplies Manufacturing Co., Chicago,
 Ill., a corporation of Illinois

Application September 17, 1947, Serial No. 774,568

10 Claims. (Cl. 153—33)

1

This invention is concerned with improvements in bending machines for cold bending of metal members.

The general object of the invention is to provide a machine for bending ductile materials, such as metal rod or pipe, which machine is light, compact, flexible in use and efficient in operation and which is adjustable to permit bending a large range of sizes of materials with a small number of adjustments or change of parts and with a minimum loss of time.

Another object of the invention is to provide an improved bending machine which will make any degree of bend on a given material up to 210 degrees without the use of split dies or the like.

A more specific object of the invention is to provide a bending machine wherein the material to be bent is clamped to a shaped form which is movable between pivoted resistance blocks to initially bend the material around the form and wherein the resistance blocks are connected by a linkage which is controlled by movement of the form to bodily move the blocks toward the form and apply additional final bending forces to the material after the initial bending operation.

A still more specific object of the invention is to provide a bending machine comprising a ram actuated form around which the material to be bent is wrapped in the bending operation, and bodily movable resistance blocks against which the material is bent, the resistance blocks being connected by linkage members, and a separable operating connection being provided between the linkage members and the form for moving the blocks towards one another and towards the form upon movement of the form between the blocks whereby the material is bent around the form with minimum clearance and with minimum distortion of the material.

Another object of the invention is to provide in a machine of the type described a ram operated bending form and a material clamping member which is operatively connected with the form operating ram whereby the material is automatically clamped to the form upon initial movement of the ram prior to the movement of the form to begin the bending operation.

A further object of the invention is to provide in a machine of the type described a reciprocal bending form and movable resistance blocks which are mounted on supporting mechanism below the level of the material being bent whereby a substantially clear flush top surface is provided where the work of bending the ma-

2

terial is to be done and complete clearance in the bending plane is afforded for greater flexibility, better access and easier operation upon previously bent shapes and whereby right and left hand bends may be made without changing the machine.

Another object of the invention is to provide in a bending machine of the type described swinging links connecting the resistance blocks which are adapted to be operated by the power ram whereby when the ram operated form has moved a predetermined distance during the bending operation the links are actuated by further movement of the ram to bodily move the resistance blocks and wrap the bent tangents of the material around the form and thereby provide bends of more than 180 degrees.

Another object of the invention is to provide a bending machine having a reciprocating shaped form and movable resistance blocks wherein provision is made for adjusting the form and blocks to adapt the machine to different sizes of materials and wherein a novel form is provided to facilitate removal of the material after it is bent.

Another object of the invention is to provide a bending machine having a reciprocating shaped form and cooperating bodily movable resistance blocks wherein automatic controls are provided for repeated operation of the machine to provide duplicate bending operations.

These and other objects of the invention will be apparent to those skilled in this art from the description of the preferred form of the machine which is shown by way of illustration in the accompanying drawings, wherein:

Fig. 1 is a side elevation with portions broken away of a bending machine embodying the principles of the invention;

Fig. 2 is a plan of the bending machine shown in Fig. 1;

Fig. 3 is an end elevation of the bending machine;

Fig. 4 is a partial plan view illustrating the position of the form and cooperating resistance blocks at the end of the bending operation;

Fig. 5 is a section on the line 5—5 of Fig. 4; and

Fig. 6 is a plan view of a piece of rod material which has been bent in the machine.

In the preferred form of the machine which is illustrated in the drawings a supporting frame or base comprising vertically arranged end channels or posts 10 and 11 supports a supply tank 12 for oil or other suitable fluid for the hydraulic

system. A driving motor 13 is mounted above the tank 12 and operatively connected by a drive shaft 14 to a pump 15 which circulates the fluid in the hydraulic system.

The motor 13 is electrically connected with a suitable power supply line and the necessary electrical apparatus is provided for controlling the operation of the same. The pump 15 is connected with a ram casing 16 by a suitable conventional fluid circulating means or system. A reversing valve 17 is provided in the system for controlling the delivery of the fluid to the casing 16. The valve is operated by solenoids 18 which are supported on an auxiliary frame 19 extending rearwardly from the rear end post 10 of the supporting frame.

The ram casing 16 is mounted at its forward end on a transverse block 20 which is secured by bolts or other suitable fastening means to the top of the rear end frame member 10. The block 20 is provided with a central aperture 21 for accommodating the ram 22 and preferably forms the end closure for the ram casing 16. The block 20 is connected by means of two parallel rod members 23 and 24 with a transverse mounting member 25 which is secured by suitable fastening means on the top of the end post 11 at the forward end of the machine. The parallel rods 23 and 24 provide a guiding and supporting means for a reciprocating block or carrying member 26 which is adapted to have secured on its top surface a shaped bending form 27.

The form supporting and carrying member 26 is provided with laterally spaced parallel bores 28 and 29 which receive the parallel guide rods 23 and 24 respectively, so that the member 26 may be freely reciprocated on the guide rods. A central bore 30 is provided in the rear portion of the member 26 for receiving the forward end of the ram 22 in freely sliding relation. A pair of laterally spaced ears 31 extend from the top forward portion of the member 26. A clamp supporting arm 32 is journaled between the ears 31. One end 33 of the arm 32 extends downwardly and is pivotally connected by a toggle link 34 with the end of the ram 22. The other end 35 of the arm 32 extends upwardly and carries a clamping plate 36 which is adapted to be moved upon operation of the ram 22 towards the bending form 27 to clamp the material to be bent to the bending form. The plate 36 is preferably provided with a concave groove 37 having a curvature approximately corresponding to the curvature of the surface of the material to be bent. The member 26 is provided on its top surface with a transverse upwardly projecting key or rib 38 which is received in a groove 39 provided in the bottom surface of the bending form 27 to properly position the form 27 on the member 26.

The form 27 is generally circular and is provided around its peripheral edge with a concave groove 40. The groove 40 has a curvature approximately corresponding to the surface of the material which is to be bent. A rear portion of the form 27 is cut away at 41 to facilitate removal of the material after the bending operation is completed. The top surface of the form 27 which may be recessed to reduce the weight, is provided with a forward aperture 42 for a threaded securing bolt 43 which is secured in the tapped hole 44 provided in the form supporting member 26. The form 27 is also provided with a vertical bore 45 for receiving an upwardly projecting pin 46.

A pair of laterally spaced resistance blocks or

pressure dies 47 and 48 are mounted for cooperation with the bending form 27. The dies 47 and 48 are generally rectangular in shape and are provided with working edges or surfaces 49, 50 and 51, 52, respectively, which are grooved to approximately correspond with the surface of the material to be bent. The dies 47 and 48 are pivoted at 53 and 54 to the rear ends of a pair of supporting arms 55 and 56, respectively. The arms 55 and 56 are pivoted at their opposite ends at 57 and 58 to the front end cross member 25 and support the dies 47 and 48 in laterally swinging relation to each other.

The die supporting arms 55 and 56 are urged outwardly to move the dies 47 and 48 towards their outermost position by means of compression springs 59 and 60 which are mounted on rods 61 and 62, respectively. The rods 61 and 62 are each pivotally connected at one end to a rearwardly extending bracket 63 which is secured to the front end cross member 25 intermediate the pivot points 57 and 58. The other ends of the rods 61 and 62 are slidingly and pivotally connected at 64 and 65 to the supporting arms 55 and 56. The springs 59 and 60 are fixed at their inner ends to the rods 61 and 62 and bear against the pivoted connections 64 and 65 at their outer ends to constantly urge the pressure dies 47 and 48 outwardly.

The pressure dies 47 and 48 are also pivotally connected at 53 and 54 to the ends of a pair of toggle links 66 and 67 which extend inwardly and are pivotally connected to each other at 68. The toggle links 66 and 67 limit the outward movement of the dies 47 and 48. One or more additional pivot points 69 and 70 are provided on the toggle links 66 and 67 to permit variable positioning of the pressure dies 47 and 48 toward each other. The toggle links 66 and 67 carry at their pivotal connection 68 a vertically extending post 71 having a rearwardly directed abutment member 72 which is provided with a recess 73 for engagement with the upwardly projecting pin 46 of the bending form 27 when the ram 22 moves forwardly a predetermined distance in the bending operation (Fig. 4). The engagement of the abutment member 72 by the pin 46 operates the toggle links 66 and 67 and moves the dies 47 and 48 bodily inwardly towards the form 27 to bend the tangents of the material around the form.

Generally U-shaped horizontal side guards or work-supporting members 74 and 75 are provided which are detachably secured at their ends 76, 77 and 78, 79 to the end cross members 20 and 25 on the main supporting frame and supported intermediate their ends by braces 80 and 81 detachably connected to the top of the supply tank or other convenient portion of the supporting frame. The members 74 and 75 are adapted to provide a horizontal surface upon which the material to be bent is rested when it is initially positioned in the machine.

The machine may be manually controlled for a single operation by push button switches 82 conveniently located at the front of the machine. The switches 82 are connected by a conventional electrical circuit with the solenoids 18 and provide for starting, stopping and reversing the ram 22 to perform the bending operation.

Automatic operating of the machine to perform repeated bending operations is provided for by limit switches 83 and 84 which are mounted on the rear end frame member 10 and downwardly projecting actuating pins 85 and 86 which

are positioned in adjustable spaced relation on the carrier bar 87.

The carrier bar 87 is secured at its forward end to a bracket 88 depending from the form-supporting block 26. The limit switches 83 and 84 are electrically connected to the solenoids 18 and control the operation of the valve 17. The actuating pins are movable on the carrier bar 87 and may be adjusted to actuate the switches 83 and 84 so as to control or limit the movement of ram 22 in both directions.

The machine is operated in the following manner. A piece of material such as a metal rod or pipe 90 (Figs. 4 and 6) is placed transversely of the machine with its ends resting on the members 74 and 75 and with the portion to be bent between the forward edge of the form 27 and the clamp 36. The initial movement of the ram 22 operates the member 36, through link 34 and arm 32, to clamp the rod 90 in position in the groove 40 of the form 27. Continued movement of the ram 22 moves the form 27 forwardly and forces the laterally extending portions of the rod 90 against the working faces 49 and 51 of the resistance dies 47 and 48 which have been manually positioned, as in Fig. 1. The dies 47 and 48 pivot or swing on the supporting members 55 and 56 about the points 53 and 54 as the ram movement is continued and wrap or bend the rod 90 around the form 27. When the center of the form 27 reaches a point approximately in the center line of the rod at the beginning of the bending action and the rod has been bent approximately 180 degrees the pin 46 engages in the recess 73 of the member 72 and actuates the toggle links 66 and 67 to bodily move the resistance dies 47 and 48 towards each other and towards the form 27 to bend the tangents 91 and 92 of the rod 90 beyond 180 degrees. The relative size and adjustment of the form 27 and dies 47 and 48 are such that without the bodily movement of the dies 47 and 48 which is effected by the toggle links 66 and 67 the rod 90 would be bent 180 degrees with a minimum of clearance between the form 27 and the dies 47 and 48. The effect of the toggle links 66 and 67 is to apply additional transverse bending forces to the tangents 91 and 92 of the material and thus obtain bends of greater than 180 degrees, particularly to compensate for resiliency in the metal. When the desired bending operation is completed the movement of the ram is reversed and the form 27 is retracted. The bent shape is then rotated around the form 27 until the cut away portion 41 permits its removal vertically from the form. The bent shape illustrated in Fig. 6 may be of material which due to its resiliency must be bent beyond 180 degrees so when it is removed from the machine the final bent shape will be the 180 degrees desired.

The machine may be adapted to bend different size materials by providing different size bending forms and resistance dies. The dies 47 and 48 are interchangeable. In the illustrated form the working surfaces 49, 51 and 50, 52 may be grooved for bending different sizes of material so that one set of resistance dies may be used for bending two different sizes of material. Any desired number of additional holes 69 and 70 may be provided in the toggle links 66 and 67 to receive the pivots 53 and 54 and to provide for varying the spacing between the dies 47 and 48. A form of the proper size may be provided for each adjustment of the

dies 47 and 48. The resistance dies 47 and 48 may also take the form of grooved wheels.

While specific details of construction have been referred to in illustrating the preferred form of the bending machine, it will be understood that other details of construction may be resorted to within the spirit of the invention.

I claim:

1. In a bending machine, laterally spaced pivotally mounted resistance blocks, mounting means for said resistance blocks, a shaped form, means mounting said form for movement between said blocks, means for moving said form, clamp means on said form for holding a piece of material to be bent against said form during the bending operation, and means connecting said clamp means to said form moving means whereby said clamp means is operated by said form moving means prior to movement of said form, said mounting means for said resistance blocks and for said form being positioned below the working level of the material being bent whereby to provide complete clearance in the bending plane.

2. In a bending machine, a supporting frame, spaced movable resistance members, a shaped form movable in a path extending between said resistance members, mechanism on said supporting frame positioned below the working level of the material being bent for mounting said resistance members and said form whereby to provide clearance in the bending plane, means for moving said form relative to said resistance members, means for moving said resistance members toward one another and toward the form upon movement of the form between said resistance members, clamp means on said form for holding a length of material to be bent between said clamp means and said form during the bending operation, and means operated by said form moving means for actuating said clamp means.

3. In a bending machine, spaced resistance blocks, a shaped form, means for reciprocating said form to move a length of material placed against said form between said resistance blocks and to bend the material around said form, a clamp mounted on said form for securing the material in position thereon, and an operating linkage connecting said clamp with said form reciprocating means whereby when said form reciprocating means is operated the material will be clamped to said form and said form will thereafter be moved relative to said resistance blocks to perform the bending operation and when the bending operation is completed the material will be released by said clamp and the form will be retracted by return movement of said reciprocating means.

4. A machine for performing bending operations, comprising a supporting frame, a shaped form mounted for reciprocating movement on said frame, means for reciprocating said form, initially bodily spaced apart resistance blocks arranged to cooperate with said form to bend a length of material placed between said form and said resistance blocks, a pair of supporting arms pivoted at one end to said supporting frame and at the other end to said resistance blocks, a cross linkage connecting said resistance blocks, said cross linkage being foldable to move said resistance blocks bodily toward each other, and interengaging members arranged to provide a temporary connection between said form reciprocating means and said cross linkage when said form is reciprocated to move said material into bending engagement with said resistance blocks,

Whereby said linkage is folded to move said resistance blocks toward each other to apply additional bending force to the material being bent as the form moves between said resistance blocks.

5. A machine for performing bending operations, comprising a supporting frame, a shaped form mounted for movement relative to said frame, a pair of initially spaced apart movably mounted resistance dies, a pair of initially extended tie links connecting said dies, said links being contractible to draw said dies bodily toward each other, power operated means connected with said form to move the same between said dies, and operating means on said form and said links to contract said links whereby to draw said dies toward each other and toward said form when said form has been moved a predetermined distance.

6. A bending machine comprising a supporting frame, a shaped form mounted for movement relative to said frame, a clamp mounted for movement toward said form for rigidly holding a piece of material to be bent against said form, resistance blocks movably mounted on said frame, a foldable linkage connecting said blocks and arranged when folded to move said resistance blocks toward each other, means slidably connected to said form and pivotally connected to said clamp for successively moving said clamp toward said form and said form toward said resistance blocks, and cooperating elements on said form and said linkage for folding said linkage to move said resistance blocks toward said form whereby, when said form and clamp moving means is operated, said material is first clamped to said form and then bent by movement against said resistance blocks and finally further bent by movement of said resistance blocks toward said form.

7. A bending machine comprising spaced resistance members, a shaped form, means slidably connected to said form for reciprocating the same to move a piece of material placed against said form between said resistance members and bend the material around said form, a clamp swingably mounted on said form for securing the material in position thereon, an arm extending from said clamp, and an operating link connecting said arm with said reciprocating means, whereby when said form reciprocating means is operated to move said form relative to said resistance members to perform the bending operation said clamp will be swung against said form to hold said material on said form, and when said form reciprocating means is operated to retract said form after the bending operation is completed said clamp will be swung away from said form to release said material.

8. In a bending machine, in combination initially spaced apart movable resistance members, a reciprocable shaped form, means for moving said form toward and away from said resistance members, a pair of initially extended link members connecting said resistance members to each other, cooperating interengaging elements on said link members and said form whereby said link members are contracted to bodily move said resistance members toward said form when said

form is moved by said form moving means a predetermined distance toward said resistance members.

9. In a metal bending machine, a supporting frame, a shaped form mounted on said frame for movement relative thereto, a clamp mounted on said form for movement toward said form to rigidly hold a length of material to be bent against said form, a movable resistance block, a supporting arm on said frame, said resistance block being pivotally mounted on said arm, a linkage pivotally connected to said resistance block, means connected to said form and said clamp for successively moving said clamp toward said form and said form toward said resistance block, and interengageable members on said form and said linkage for moving said resistance block toward said form upon predetermined movement of said form toward said resistance block, whereby said material is first clamped to said form and then bent by relative movement of said form and said resistance block.

10. In a machine for performing bending operations, a reciprocable frame adapted to receive different size bending forms, a pair of movable arm members, resistance blocks pivotally mounted on said arm members, a pair of initially extended foldable cross tie links connecting said resistance blocks, power means for reciprocating said form carrying frame, and interengaging abutment members on said frame and said tie links operating to bodily move said resistance blocks relative to said form carrying frame upon predetermined movement of said form carrying frame, said resistance blocks being adjustably connected with said tie links whereby the size of the bend may be varied by placing different size forms on the form carrying frame and adjusting the resistance blocks relative to the tie links to cooperate with the respective form.
